UNITED STATES PATENT OFFICE.

HENRY R. WOODWARD, OF NEW YORK, N. Y.

NOSTRIL-EXPANDER..

No. 851,048.

Specification of Letters Patent.

Patented April 23, 1907.

Application filed August 1, 1906. Serial No. 328,788.

To all whom it may concern:

Be it known that I, HENRY R. WOODWARD, of the city, county, and State of New York, have invented a new and Improved Nostril-5 Expander, of which the following is a full, clear, and exact description.

My invention relates to improvements in nostril-expanders.

I have found that with many people the 10 tendency while breathing is for the nostrils to collapse more or less or at least become somewhat restricted so as to interfere with breathing. This is particularly true when people are engaged in athletic sports—such as 15 running, racing, or any effort which requires a large supply of air to the lungs—and in such exercises the tendency is to open the mouth, thus admitting impurities and also causing the mouth to dry quickly. I have found also 20 that the habit of snoring is caused largely by this constriction of the nostrils, or at least if the nostrils are kept well expanded snoring ceases.

The object of my invention is to obviate 25 these difficulties and produce a cheap and simple device which can easily be applied to the nose and which can be worn without discomfort. This device is intended to enter 30 the nostrils and prevent them from closing, thus permitting a free air-current to pass through them.

A further object of my invention is to construct the device so that it can do no injury, cannot accidentally enter the head, and can 35 be easily removed when desired.

With these and other ends in view my invention consists of a nostril-expander, the construction and use of which will be hereinafter described, and the novel features of 40 construction claimed.

Reference is to be had to the accompanying drawings, forming a part of this specification, in which similar letters and figures of reference indicate corresponding parts in all 45 the views.

Figure 1 is a side elevation, partly diagrammatic, showing the application of my invention to the nose. Fig. 2 is a similar view showing a slightly-modified form of the 50 apparatus. Fig. 3 is a detail perspective view of a preferred form of the device such as shown in Fig. 1, and Fig. 4 shows a slight modification and is similar to the structure shown in Fig. 2.

55 The apparatus is made, preferably, of spring-wire, though obviously it can be made of any

material which will be springy, will hold its shape, and will not injure the wearer.

While I do not limit myself to the particular or precise form shown, still it is better to make it as illustrated, and here the structure has a point or bridge 10 in Fig. 3, or 10^a in Fig. 4, which straddles the cartilage of the nose, and from this point the members diverge slightly, as shown at 11, and are then 65 bent upward and rearward, as at 12, so as to follow the normal contour of the nostril, the said members 12 being bent over gradually and returned upon themselves, as shown at 13, and finally terminating in inturned bends 70 14. It will be seen that this arrangement forms a springy loop more or less elongated for entering each nostril, and as the loops are connected no injury can be done, while the bends 14 enable the device to be easily withdrawn without the possibility of the parts 75 catching into the skin.

It will be seen that the principle of the invention consists in providing the springy loops which will prevent the nostrils from 80 collapsing and in connecting the loops so that they cannot extend inward too far and can be easily and instantly withdrawn. It is necessary, however, to have the loops rather long, so that they will extend back into the 85 nasal cavity of the head, and they should lie in a generally horizontal direction, with the connecting-bridge 11 bent down, so as to straddle the cartilage of the nose.

In practice I have found that this device 90 assists breathing under all conditions where the breath is more or less forced, that it enables a large supply of air to enter the lungs, is therefore good for singers, and is also valuable to assist breathing where one has a head-cold. 95

Having thus fully described my invention, I claim as new and desire to secure by Letters Patent—

A device of the kind described comprising 100 a pair of elongated open loop-like members of spring material having their terminal ends bent, and constructed to extend backward into the nasal cavity of the head, the said members being connected at the forward 105 ends by a bridge, which is bent at an angle to the said members so as to straddle the nose-cartilage. 110
